UNITED STATES PATENT OFFICE

ARTHUR ISHERWOOD, OF BOSTON, MASSACHUSETTS, ASSIGNOR TO THOMAS KENYON,
OF MANCHESTER, ENGLAND.

CLOTH SPREADER OR EXPANDER.

1,233,059.

Specification of Letters Patent. Patented July 10, 1917.

Application filed December 2, 1915. Serial No. 64,638.

To all whom it may concern:

Be it known that I, ARTHUR ISHERWOOD, a citizen of the United States, residing at Readville, Boston, in the county of Suffolk, State of Massachusetts, have invented a certain new and useful Improvement in Cloth Spreaders or Expanders, of which the following is a specification, reference being had therein to the accompanying drawings.

- 10 The invention comprises improvements in cloth spreading or expanding devices on the order of the well-known Mycock spreader or expander, one form of which is shown and described in U. S. Letters Patent to W. Mycock No. 687,847, granted Dec. 3, 1901. The said improvements are applicable to a variety of spreaders or expanders of the same general type as that shown and described in the said patent.
- 20 The improvements comprise, first, intermediate or so-called center-supports for the curved supporting rods on which are mounted the revoluble serrated disks, blocks, or "clutches" which are engaged by the cloth in its passage; secondly, drag or brake devices by which the disks, blocks or clutches are held from loose or idle forward and backward turning movements, and whereby the inter-engaging lugs or shoulders of adjacent disks, blocks or clutches are kept in firm driving engagement with one another; thirdly, an improved construction providing for taking care of the inward end-thrust of the clutches toward a central support, and 35 obviating wearing of the bearing portions of the said support and the two clutches adjoining the same.

The drawings show the improvements conveniently embodied and combined in a 40 spreader or expander of the type mentioned above, the said spreader or expander being shown in connection with a calender of ordinary character.

In the drawings,—

- 45 Figure 1 is an elevation of certain portions of a calender with the improvements applied thereto, certain small portions being broken out at the middle of the machine.

Fig. 2 shows in plan the parts of Fig. 1, 50 the top roll of the calender being omitted.

Fig. 3 is a view on a somewhat larger view than Figs. 1 and 2, on a slightly larger scale, of a calender with the improvements applied thereto.

55 Fig. 4 is a view on a still larger scale show-

ing the lower central supports in side elevation, and representing in vertical cross-section the carrying support therefor.

Fig. 5 is a view in section in the plane of line 5, 5, of Fig. 4.

60 Figs. 5^a and 5^b are detail views of the bolt-disengaging device hereinafter described.

Fig. 6 is a detail view of the drag or brake-devices at one end of one of the 65 spreading or expanding elements.

Fig. 7 is a view looking from the right-hand side in Fig. 6.

70 Fig. 8 is a sectional view showing the construction of the bearings at one of the central supports, and the manner of taking up end-thrust.

Having reference to the drawings,—

The frame of a calender, partly shown therein, is marked 1, and the top, middle and 75 bottom rolls thereof respectively are marked 2, 3 and 4. The spreader or expander is located at the side of the calender at which the cloth travels toward the latter, and the cloth passes through the spreader or expander and then between the middle and bottom rolls 3 and 4 of the calender, etc. The spreader or expander shown in the drawings comprises five complete spreading or expanding elements which, for the purposes of this description, may be termed "expander-bars." As usual, each of the said 80 expander-bars comprises a curved non-rotating shaft or bar 5, which is connected at its ends to supporting stands 6, 6, at the opposite sides of the machine, and a number of serrated disks, blocks, or clutches 7, 7, etc., carried by the said non-rotating shaft or bar and capable of turning or rotating thereon. The cloth on its way through the 85 spreader or expander passes under and over the said expander-bars in alternating succession as shown best in Fig. 3. The expander-bars are bent or bowed toward the delivery-side of the expander or spreader so 90 that the cloth arrives at each expander-bar in succession at the short or concave side thereof and leaves the same at the long or convex side thereof, and therefore is spread, or expanded widthwise, all 95 as is well understood by those skilled in the art. As usual, also, the expander-disks, blocks or clutches are formed at the ends thereof with longitudinally projecting lugs,

100 as indicated in Figs. 1 and 2, those of each 105 Fig. 4 being shown at 110

disk, block, or clutch in turn occupying spaces between the ones on the adjacent disks, blocks or clutches, so as thereby to clutch a series of the disks, blocks or clutches together and compel them to rotate around the supporting bar substantially in unison. In other words, the disks, blocks, or clutches of a series mounted upon a fixed curved supporting shaft or bar are interlocked with one another so as to turn in unison. All that has been referred to thus far is well known in the art.

In use, the strain of the cloth passing around the expander-bars has a marked tendency to spring the bowed portions of the expander-bars up or down as the case may be; that is to say, in a direction at right-angles or approximately right-angles to the plane of the cloth. The intermediate or so-called center supports constituting the first improvement comprise one set thereof which is applied and contrived to resist the tendency to spring certain of the expander-bars upward, and a second set which is applied and contrived to resist the tendency to spring the remaining expander-bars downward. The center supports by which the upwardly-acting strain is counteracted comprise in the present embodiment of the invention two transversely extending tubes 8, 8, which are fixedly mounted at their ends in stands 9, 9, projecting from the side frames of the calender. Upon these tubes a depending double bracket 10 is fixed at the middle of the width of the machine, the said double bracket having branches which are provided with eyes 12, 12, 12. The said eyes may surround and fit the supporting bars or shafts of the first, third, and fifth expander-bars, *i. e.*, those expander-bars under which the cloth passes, or the clutches which immediately adjoin the eyes 12, 12, may be furnished with suitable journal-bearings in connection with the eyes, as presently is explained herein. The strain in the case of the expander-bars named is of course upwardly. The support which has just been described resists the tendency of the upwardly directed strain to spring the middle portions of the said expander-bars upward. The eyes, 12, 12, 12, separate the disks, blocks, or clutches of each expander-bar into two series, each series being about one-half the length of the expander-bar. The said eyes, exteriorly, do not exceed in diameter the adjacent clutches. See, more particularly, Fig. 8. Consequently they do not interfere with the web or prevent it from entering into flat contact with the surfaces of the said clutches. The middle portions of the second and fourth expander-bars, namely those alternating with the ones first mentioned, and being the ones over which the cloth passes, so that the tendency of the strain is to press the said middle portions

downward, have combined therewith eyes 13, 13, Figs. 4 and 5, on the upper ends of bars 14, 14, sliding in vertical sockets in the double grip-bracket 15 which is fixedly mounted on the transversely extending fixed tube 16, the latter being supported at its ends by brackets 17, 17, projecting from the side-frame of the calender. The said eyes 13, 13, etc., sustain the middle portions of the second and fourth expander-bars against the effects of downwardly acting strain. Like the eyes 12, 12, etc., they are so proportioned as not to prevent the web from lying properly in contact with the surfaces of the clutches which adjoin them on opposite sides thereof, and like the eyes 12, 12, etc., they may be fitted to the supporting-rods themselves or may be provided with journal-bearings for the central clutches. In practice, the expander-bars of a spreader or expander are made adjustable, as by the adjustment devices *a*, *a*¹, *a*², shown in the drawings, so as to interlap with one another, or not at all, according to the nature of the cloth operated upon, and according as a greater or less spreading or expanding action is required. To accommodate this adjustment, which in the illustrated machine involves movement of the second and fourth expander-bars up and down relative to the first, third and fifth bars, the central supports for the second and fourth bars likewise are made adjustable. Thus, the bars 14, 14, are fitted within the sockets of the double grip bracket 15 with capacity to be moved up and down within such sockets. To support them at the required height locking devices are employed. The locking devices in connection with each bar 14 comprise in the present instance a bolt 18, actuated by a spring 18^a, which presses the bolt toward the bar 14, and this latter is formed with rack-teeth 14^a, with which the acting portion of the bolt engages. As a result of such engagement, the bars 14, 14, and the middle portions of the length of the corresponding expander-bars, after adjustment, are held against the depressing action of the cloth upon such expander-bars. In order to render the center support for the second and fourth expander-bars automatically adjustable in case of adjustment of the second and fourth expander-bars upward, the rack-teeth 14^a, 14^a, of the bars 14, 14, are formed with inclined upper sides, and the engaging portions of the bolts 18, 18, are correspondingly formed so that the said rack-teeth will slip readily upward past the bolts as the bars 14, 14, are raised in consequence of upward adjustment of the second and fourth expander-bars, but the engagement of the bolts with the under sides of the said rack-teeth will hold the bars 14, 14, from descending. When it is desired to lower the second and fourth expander-bars the bolts are disen-

gaged from the rack-teeth by outward movement of the bolts. This disengagement is conveniently provided for in the case of each bolt in the present instance by means of a disk 19, Figs. 5, 5^a, fitted upon the exposed outer end of the stem of the bolt and adapted to turn thereon, it having projecting wings or flanges to enable it to be grasped or engaged for the purpose of applying force to turn it. The inner face of the said disk is formed with a cam or projection 19^a normally occupying a notch in the disk 20 through which the said stem of the bolt works. So long as the projection or cam is in the notch the spring is permitted to hold the bolt in engagement with the rack-teeth. When, however, the disk 19 is turned so as to cause the projection or cam to ride out of the notch and up on the outer surface of the disk 20, the disk 19 and with it the bolt are moved outward so as to draw the acting portion of the bolt out of engagement with the rack-teeth, thereby freeing the bar 14 so that it may be shifted as required.

A drawback in connection with expanders or spreaders as constructed heretofore has been the fact that in use the clutches which are outside the selvages of the cloth, and consequently not engaged directly by the cloth but caused to rotate around the supporting shaft or bar by reason of the interengagement of the lugs of the clutches with one another, are from time to time thrown forward by the driving action of the clutches which are engaged and rotated by the cloth, but faster than these latter clutches, so that in consequence of back-and-forth shifting or chucking action of these outside clutches considerable noise and wear result through the lugs or wings hammering against one another. To remedy this, I provide a yielding drag or brake acting in connection with the terminal clutch at each end of an expander-bar so as to control the rotation of the same and prevent it from springing or being thrown forward. Through the interengagement between the lugs of the terminal clutch with those of the next adjacent clutch, and so on throughout the series, a checking or braking action is transmitted to all of the clutches of the series, thereby holding the interengaging lugs of all the clutches of the series firmly pressed together in close and continuous driving contact. In its preferred form, the drag or brake-device comprises a spring-pressed collar 21, Fig. 6, fitting around the supporting rod or shaft 5 of an expander bar adjacent the outer terminal clutch 7 at such end, and acting against the outer end of the said terminal clutch, preferably through an interposed washer 22 of suitable friction-producing material, for instance raw-hide, interposed between it and the said terminal clutch.

The collar 21 is held from turning with the clutches. This may be provided for in different ways. In this instance, a series of pins or studs 23, 23, 23, projects outwardly from the collar 21 through holes in another collar, 24, which is fastened upon the supporting shaft or bar by means of a clamping screw 25 so as to prevent it from turning thereon. The pins 23, 23, 23, are capable of sliding through the holes in the fixed collar 24 so as to permit the collar 21 to move in the direction of the length of the supporting shaft or bar, and in this instance the collar 21 is pressed with yielding force toward the adjacent terminal clutch by means of expanding spiral springs 26, 26, surrounding the said pins and confined between the two collars. A weighted lever would be an equivalent for the springs shown but in most cases the latter are most convenient. The means of keeping the clutches pressed together endwise operates to keep them with their end-faces in contact and their interengaging lugs in close and continuous driving contact.

Referring now to the improved construction which provides for taking care of the inward end-thrust of the clutches toward a central support, and obviating wearing of the bearing portions of the said support and the two clutches adjoining the same: This improvement is designed to take care of the inward end-thrust of the two opposite sets of clutches of an expander-bar toward the central support of the latter, and to guard against the wearing of the bearing portions, as well as against injury to the cloth through staining or marking by metallic particles.

This improvement is shown in Fig. 8. In accordance therewith, each of the central supports has the eye thereof, 12 or 13 as the case may be, lined with two bushings 12^a, 12^a, placed side by side and having their inner surfaces crowned transversely, and the two adjacent clutches at opposite sides of the said eye are formed with reduced cylindrical extensions 7^a, 7^a, which fit within the two crowned bushings and have their exteriors in bearing contact with the said crowned surfaces. These bearing extensions are bored out slightly larger than the supporting bar 5 and have fitted within them bushings 7^b, 7^b, which interiorly fit the said bar 5 and turn thereon. External flanges upon these bushings 7^b, 7^b, engage with the ends of the bearing portions 7^a, 7^a, of the two clutches, to limit the extent to which the bushings can enter into the bearing extensions 7^a, 7^a, and these bushings make contact with each other by their adjacent ends under the end-thrust which operates to keep the clutches pressed inwardly toward the center support from the opposite ends of the expander bar. The bushings 12^a and 7^b are removable and replaceable. In

practice I usually combined with them suitable anti-friction material, such as metalle, graphite, or the like, ordinarily applied in pockets. In this construction I dispense with a fixed intermediate end-thrust bearing, and provide the two innermost clutches with meeting portions which rotate in unison, so that frictional contact between the said clutches and a fixed intermediate end-thrust bearing is done away with altogether. In case of extra strain or tension on the cloth tending to force or strain the clutches upward or downward, the bearing extensions 7^a, 7^a, will rock slightly on the rounded surfaces of the crowned bushings 12^a, 12^a. As will be perceived, the rocking action may take place independently at either side of the central support.

The grip or hold of the disks, blocks, or clutches of the expander-bars upon the cloth passing through the spreader or expander, and consequently the effectiveness of the spreading or expanding action, are in proportion to the tension of the cloth as it passes through. The degree of tension determines the degree of the pressure of the cloth against the surfaces of the clutches, and therefore the grip or hold of the said surfaces upon the cloth. In preparing the cloth which is to be operated upon in a calender a considerable number of pieces are stitched together end to end and wound together in a roll of large diameter, such roll being termed a batch-roll, or for short a "batch." The outside pieces of the batch are usually, if not always, more slackly or loosely wound than those at the interior. Consequently, under ordinary conditions the said outside pieces pass through a spreader or expander under a less degree of tension than those forming the inner portion of the batch. As a result, difficulty is experienced in keeping the first piece or pieces of the batch out to the predetermined width. To remedy this difficulty I provide a tension-regulating device at the entrance to the spreader or expander, which acts upon the cloth as the latter passes from the batch to the spreader or expander and which is so constructed as to be readily adjustable so that its action may be varied from time to time as may be required in order to secure substantial uniformity in the tension of the cloth in entering the spreader or expander notwithstanding differences in the tightness with which different portions of the batch are wound, and so as to maintain uniformity in the efficiency of the spreader or expander and enable the cloth throughout to be given the same width.

The tension regulating device aforesaid is arranged to act upon the moving web of cloth itself after the latter has left the batch. It comprises in the present instance two bars, 26^a and 27, partly around each of

which the cloth passes, so that the cloth is bent out of a straight path and also held in frictional contact with the surfaces of the bars. The bars are adjustable relatively to each other so that the cloth may be caused to enwrap each of the bars more or less, as the case may be, and thereby increase or decrease the resistance to the forward travel of the cloth. Herein, the rod 27 is hung by arms 28, 28, so that it may be shifted in an arc around the rod 26^a, and it is held in the desired position of adjustment by means of a dog or pawl 29, Figs. 1 and 2, engaging with the teeth of a fixed ratchet-wheel 30.

I claim as my invention:—

1. In combination with an expander-bar comprising a bowed supporting-rod and clutches mounted upon said supporting-rod and operating to expand widthwise a web traveling past the same, means for adjusting the ends of said expander-bar at right angles to the plane of the web, an intermediate support for said expander-bar having a rack and adapted to be adjusted correspondingly with the said ends, and a bolt engaging with the rack to hold the intermediate support in adjusted position. 70

2. In combination with a series of expander-bars, each comprising a bowed supporting-rod and clutches mounted thereon and operating to expand widthwise a web traveling partly around the respective expander-bars alternately, intermediate supporting means for the expander-bars at one side of the web and intermediate supporting means for the intervening expander-bars at the other side of the web. 85

3. In combination with a series of expander-bars, each comprising a bowed supporting-rod and clutches mounted thereon and operating to expand widthwise a web traveling partly around the respective expander-bars alternately, intermediate supporting means for the expander-bars at one side of the web and intermediate supporting means for the expander-bars at the other side of the web, means for adjusting the ends of the expander-bars to vary the alignment thereof, and means for effecting corresponding relative adjustment of the intermediate supporting means. 100

4. In an expander, the combination with a series of expander-clutches and means for supporting them in line with one another in position for expanding a traveling web, of drag or brake devices holding the said clutches from loose or idle forward and backward turning movement. 110

5. In an expander, in combination, a supporting-rod, a series of expander-clutches mounted on said supporting-rod and revoluble thereon under the action of the traveling web, and drag or brake devices holding the said clutches from loose or idle forward and backward turning movement. 125

6. In an expander, in combination, a supporting rod, a series of expander-clutches mounted on the said supporting-rod and revoluble thereon under the action of the traveling web, and drag or brake devices in connection with said clutches including a spring-pressed collar operating to keep them pressed together endwise and also to keep them from loose or idle forward and backward turning movement.

7. In an expander, in combination, a supporting-rod, a series of expander-clutches mounted on the said supporting rod and revoluble thereon under the action of the traveling web, and drag or brake devices in connection with said clutches operating to keep them pressed together endwise and also to keep them from loose or idle forward and backward turning movement, and comprising a spring-pressed collar non-rotatively mounted upon the supporting-rod.

8. In an expander, in combination, a series of rotatable expander-clutches, means for supporting such series in line with one another endwise, and an intermediate support in which intermediate clutches of the series are journaled.

9. In an expander, in combination, a series of rotatable expander-clutches, means for supporting such series in line with one another endwise, and an intermediate support in which the central clutches of the series are journaled in end-thrust engagement with each other.

35 10. In an expander, in combination, a se-

ries of rotatable expander-clutches, means for supporting such series in line with one another endwise, and a central support provided with internal journal-bearings for the meeting-ends of the central clutches and 40 within which bearings the said meeting-ends are in end-thrust engagement with each other.

11. In an expander, in combination, a series of rotatable expander-clutches supported in line with one another endwise, the central clutches having reduced meeting-ends, and a central support within which the said meeting-ends are in end-thrust engagement with each other, the said support 45 50 having internally-crowned bearing-surfaces within which said meeting ends are journaled.

12. In an expander, in combination, a series of rotatable expander-clutches, a bowed supporting-rod on which the said clutches are mounted in line endwise with one another and on which they revolve, the central clutches of said series having reduced meeting-ends, a central support within which 55 60 the said meeting-ends are journaled, removable end-thrust bearing members in connection with said meeting-ends, said bearing-members fitting the said supporting-rod.

In testimony whereof I affix my signature in presence of two witnesses.

ARTHUR ISHERWOOD.
